CONTAINER PACKAGE AND DISPENSER FOR
PRESSURE-SENSITIVE TAPE

Alfred P. Krueger, Stratford, and Oscar P. Erhardt, Derby, Conn., assignors to Derby Sealers, Incorporated, Derby, Conn., a corporation of Connecticut

Application September 29, 1948, Serial No. 51,812

9 Claims. (Cl. 206—52)

1

This invention relates to a tape dispenser and, more particularly, to a device for dispensing pressure-sensitive tape which is tacky or clingable upon one surface and usually is relatively narrow.

Such tape is commonly sold in rolls, the rolls being packed in their container or case from which they are removed and usually placed in a machine from which they are dispensed.

We contemplate, by the present invention, providing a case or container which will rotatably support a roll or rolls of tape and so constructing the container that the tape may be dispensed therefrom without the necessity of employing a separate dispensing device.

To this end, the container is provided with an opening through which the tape may be drawn from the roll, and is also provided with a tear-off blade or severing member against the edge of which the tape may be torn off when a sufficient length has been unwound from the roll. Moreover, these elements are so arranged that when the length of tape has been severed, a free end will remain projecting from the container or case so that it may be readily grasped by the fingers of the operator for a succeeding operation.

A device of this character makes it possible for the tape to be packed and sold in the dispensing container, and not only renders it unnecessary for the users of the tape to purchase a separate dispenser, but eliminates the inconvenience of having to remove the tape from the container in which it is bought and mount it in a separate dispenser.

One object of our invention is to provide a novel and simple dispensing case or container for a roll of tape.

A further object of the invention is to provide a case or container which is provided with means for rotatably supporting a roll of tape, and which is also provided with a tear-off blade and an opening adjacent this blade so that the tape may be dispensed from the container in which it is packaged and sold.

A still further object of the present invention is to provide a dispensing case or container for pressure-sensitive tape so constructed that it may be cheaply and economically made and which, at the same time, may be employed as a tape dispenser, so that a roll of tape may be dispensed from the roll or container in which it is packaged and sold.

To these and other ends the invention consists in the novel features and combinations of parts to be hereinafter described and claimed.

2

In the accompanying drawings:

Fig. 1 is a front elevational view of a tape container and dispenser embodying our invention, with some parts broken away;

5 Fig. 2 is a sectional view on line 2—2 of Fig. 1; Fig. 3 is a top plan view of the container and dispenser;

Fig. 4 is a partial sectional view on line 4—4 of Fig. 2;

10 Fig. 5 is a rear elevational view of a container and dispenser of modified form;

Fig. 6 is a sectional view on line 6—6 of Fig. 5; Fig. 7 is a sectional view on line 7—7 of Fig. 6;

15 Fig. 8 is a top plan view of a container of modified form;

Fig. 9 is a sectional view on line 9—9 of Fig. 8;

Fig. 10 is a top plan view of still another form of container; and

Fig. 11 is a sectional view on line 11—11 of 20 Fig. 10.

To illustrate a preferred embodiment of our invention, we have shown a container or case comprising a body portion 10 of circular form, provided with a peripheral wall or flange 11. The body of the case may be closed by a cover 12, which cover is provided with a peripheral wall or flange 13 which telescopes over the upper portion of the flange 11.

The body portion 10 of the case is displaced 30 inwardly at its central portion as shown at 14 to provide an annular shoulder 15 upon which is designed to be received a supply roll of tape 16, this tape being wound upon a hollow reel or spool 17 of circular form which fits over the annular shoulder 15.

Likewise, the cover is provided with an inwardly displaced portion 19 which provides an 35 annular shoulder 20 upon which is also adapted to be received a second roll of tape 16 also wound

40 upon the spool 17. The two rolls of tape are designed to be separated or spaced apart by a disk-shaped spacer member 21, this spacer member being provided with a central opening to receive the displaced portion 14 of the body portion 45 of the case and, thereby, be held in place. It will be noted that the shoulder 15 is slightly wider than the shoulder 20 so that it will be sufficiently wide to accommodate both the roll 16 and the spacer element 21.

It will be found expedient to provide this 50 spacer element, in that, in the operation of the device one of the rolls will be rotated when the tape is unwound therefrom, while the other roll, which is not being used at that time, will remain 55 at rest.

When the roll (the one on the right, as shown in Fig. 2) has been exhausted, it will be removed and the other roll put in its place. The empty spool 17 may then be placed in the other part of the case against the spaced element so as to hold the roll which is being used in the proper position, as the tape is dispensed from one side only of the case.

As shown more especially in Figs. 1, 3 and 4, the body portion of the case is provided with spaced openings 23 and 24 and, adjacent one edge of the opening 24, the metal of the case is turned outwardly in a radial direction so as to provide a lip 25 which serves as a tape-end support to which the free end of the tape may cling, so as to hold this end in an exposed position where it may be more readily grasped by the operator. It will be understood that, as shown in Fig. 1, for example, the free end 26 of the tape, which comes from one of the rolls 16, is drawn from this roll through the opening 24, to be dispensed.

Mounted within the case and in relatively snug relation with the flange 11 of the body portion 10 is a resilient sheet metal ring 28. This ring may be, as shown, of substantially the same width as the flange 11, although this may be varied as desired, and is split or discontinuous as shown at 29 so that by its natural resilience it will tend to expand against the flange 11.

Adjacent the opening 23, the ring is provided with an outwardly protruding finger piece 30 which projects outwardly through the opening 23 of the case, so that it may be engaged by the operator. This member 30 may be formed by striking the metal of the resilient member 28 outwardly, or it may be constructed as a separate piece and welded to the member 28 as shown in the drawing. It will preferably fit fairly snugly in the opening 23 so as to be guided thereby and, as will be noted in Fig. 3, the width of this opening is considerably smaller than the width or height of the flange 11.

The member 28 is also provided with an opening 32 which is arranged in juxtaposition to the opening 24, this opening being of sufficient width to permit the tape to issue therethrough when it is in registration with the opening 24, which is also of substantially the same width as the tape.

Adjacent one edge of the opening 32, a tear-off blade or severing member 33 is carried by the resilient sheet metal member 28. As shown, more especially, in Figs. 1 and 3, this severing member 33 is displaced outwardly or in a radial direction from the periphery of the case and it may be formed by striking outwardly the metal of the member 28 so as to leave the opening 32, or it may be formed by a separate Z-shaped member secured to the member 28 as illustrated. The member 33 will be spaced outwardly from the case a sufficient distance to clear the tape-end support or lip 25, so that in one position of the member 28 it will cover this lip, as shown in Figs. 1 and 3 of the drawings.

The normal position of the parts is shown in full lines in Fig. 1 and it will be apparent that the free end of the tape 26 extends outwardly from the adjacent rolls 16 through the openings 32 and 24 between the lip 25 and the radial portion 34 of the severing element 33 and then circumferentially along this severing element to the free edge thereof, where it presumably has been severed in a previous operation.

If the operator desires to draw some tape from the roll, the member 28 is moved in a counter-clockwise direction, as shown in Figs. 1 and 4, by

pressure of the thumb or finger of the operator on the member 30, moving it to the opposite end of the slot 23. This moves the severing member 33 to the position shown in Fig. 4, so that the free end 26 of the tape and the lip 25 are uncovered, thus leaving the projecting end of the tape in an exposed position so that it may be readily grasped by the operator. The tape is now drawn from the roll which rotates on the annular shoulder 15 until a sufficient length has been unwound. Thereupon, the operator, by pressure of his thumb or fingers on the member 30, moves the element 28 in the opposite direction, thus moving the severing member 33 in a clockwise direction to a position in which it covers the tape-end support 25, and also a length of the tape beyond this support, this length standing between the support and the free severing edge of the element 33. The tape is now torn off against this free edge of the element 33, as shown in Fig. 1, thus, leaving a length of tape lying along the under or inner side of the element 33, and restoring the parts to the position shown in Fig. 1.

In Figs. 5 to 7 of the drawings, we have shown a modification in which the dispenser as before consists of a container having the two parts or sections, a body portion 40 and cover 41 provided respectively with flanges 42 and 43 which nest together when the sections are placed in closed position and secured in this position by the screw 44. This screw is eccentrically located to hold the parts against relative rotation. The supply roll 16 is supported as before on the shoulders 45 and 46 of the inwardly displaced central portions of the two sections of the case. In this form of our invention, the outer flange 43 is interrupted or provided with an opening 56 of considerable length, and the inner flange 42 is provided with a shorter opening or interrupted portion 57. At one end of this opening, the inner portion is provided with a radially projecting tape-end support 58 against which the tacky side of the tape is adapted to engage and cling.

Slidably mounted on the flange 42, as shown more particularly in Figs. 5 and 7, is an arcuate slide 59. This slide is provided with a slot 60 within which projects a pin 61 secured to the flange 42, and a tension spring 62, secured at one end to this pin and, at the other end, to the rear end of the slide 59, serves to urge the slide to the full-line position shown in Fig. 7. The slide is also provided with a manually engageable finger piece 63 which is slidably received in a slot 64 in the flange 42, so that the slide 59 may be manipulated or moved about the flange 42 by the finger piece 63 against the tension of the spring 62.

At the forward end, the slide is provided with an outwardly displaced severing member 65 which serves in the closed position of the parts, as shown in Fig. 5 and in full-lines in Fig. 7, to cover the tape-end support 58 and it will be noted that the slide 59 itself normally closes the opening 57 in the inner flange.

Normally the parts are in the position shown in Figs. 5 and 7 in which the free end of the tape extends from the roll 16 over the lip or tape-end support 58 with which its tacky surface is engaged, and then circumferentially of the case to the cutting edge of the severing member 65. When it is desired to draw tape from the dispenser, the operator, by placing his finger on the element 63, may move the slide 59 rearwardly to the dotted-line position shown in Fig. 7, thus, moving the severing member 65 away from the tape-end support 58 so as to uncover a portion of

the opening 57. A free end 67 of the tape will now project from the tape-end support 58 and the operator may grasp this end and pull the tape outwardly unwinding it from the roll. When a sufficient length has been pulled outwardly, the finger piece 63 will be released and the slide 59 will be returned by the spring 62 from the dotted-line position shown in Fig. 7 to the full-line position. The tape may now be torn off against the free edge of the severing member 65.

It will be seen that the split ring 28 which constitutes the slide in the form of our invention shown in Figs. 1 to 4 of the drawings is held in the casing only by its inherent tendency to expand which causes it to snugly hug the periphery of the body portion of the case. It may, therefore, be readily inserted into the case by simply bringing the free ends into overlapping position and, thus, contracting the ring until the projection 30 and the severing member 33 may enter the openings in the case. This split ring slide may also be readily detached from the case and it may be found convenient to sell tape in the improved case without the slide, the slide being inserted after the container or case has been opened.

To this end, we have illustrated in Figs. 8 and 9 of the drawings a case provided with openings 23^a and 24^a which openings are adapted to receive the projection 30 and the severing device 33 of the split ring 28. In order, however, that the container may be sealed so that the tape will not be affected by the atmosphere, a strip of paper or tape 10 may be pasted over these openings to seal them.

Thus, one or more spools of tape may be sold in such a container which will be sealed until it is desired to use the tape. At that time, the strip of paper or tape 10 may be removed, the cover 12 removed from the body portion 10, and the split ring 28 inserted.

In making the opening 24^a, the metal adjacent two of the corners of the opening at one side is slit for a short distance beyond the end of the opening, as shown at 24^b, so as to leave a short length of material 25^a which may be bent upwardly to form a lip corresponding to the lip 25 shown in Fig. 1. It will be understood, of course, that this lip 25^a will lie within the outline of the surrounding material until after the strip 10 is removed after which it may be bent up to the desired position.

In Figs. 10 and 11 of the drawing, we have shown a similar construction in which the metal of the case 10 is not entirely cut through, but is merely partially punched out to provide knock-out plugs 71 and 72 bounded by weakened lines 73 and 74. These plugs may be readily removed by the user and, when removed, will leave openings in the case to receive the projection 30 and the severing member 33. Therefore, in this form of our invention, there is also provided a container which will be sealed until the contents are desired to be used. Then the plugs 71 and 72 may be knocked out and the split ring inserted after the case is opened.

In this instance, the weakened lines are extended at one end of the knock-out plug 72 as shown at 75, so that after the plug 72 has been knocked out the short piece of metal 25^b between the weakened lines 75 may be turned upwardly to provide a lip corresponding to the lip 25 shown in Fig. 1 of the drawings.

While we have shown and described some preferred embodiments of our invention, it will be

understood that it is not to be limited to all of the details shown, but is capable of modification and variation within the spirit of the invention and within the scope of the claims.

5. What we claim is:
1. A tape-dispensing device comprising a casing provided with a body portion having a circumferential flange and means for rotatably supporting a roll of tape, said flange having an opening therein and a radially extending lip adjacent said opening, a slide movably mounted on the inner surface of the flange for movement to closed and open positions to cover and uncover said opening, and a severing member carried by said slide and said severing member being displaced outwardly from the slide so as to clear said lip and be moved thereover.
  2. A tape-dispensing device as in claim 1, wherein the slide comprises a resilient expansible member mounted within said flange and urged by its resiliency against said flange.
  3. A tape-dispenser as in claim 2, wherein the flange is provided with a second opening and the slide is provided with a finger piece projecting outwardly through said opening.
  4. A tape-dispensing device comprising a casing having a body portion with a circumferential flange and means for rotatably supporting a roll of tape, said flange having an opening therein and one edge of said opening being turned outwardly to form a radially projecting lip, a slide movably mounted on the flange for movement to closed and open positions to cover and uncover said opening, and a severing member carried by the slide and projecting over said lip when the slide is in closed position.
  5. A tape-dispensing device comprising a casing provided with a body portion having a circumferential flange and means for rotatably supporting a roll of tape, said flange having an opening therein and a radially extending lip adjacent said opening, a slide movably mounted on the flange for movement to closed and open positions to cover and uncover said opening, and a severing member carried by said slide, said severing member being displaced outwardly from the slide and projecting beyond the slide to cover the lip and extend circumferentially beyond said lip when the slide is in closed position, whereby, when the tape is severed against said member, a free end thereof will project beyond this lip.
  6. A tape-dispensing device as in claim 5, wherein the slide comprises an expansible resilient member mounted within the flange, and said severing member extends outwardly through said opening in the flange to the outside of the case.
  7. A tape-dispensing device comprising a casing provided with a circular body portion having a circumferentially extending flange, means within the casing for rotatably supporting a roll of tape, said flange being provided with an opening through which the free end of the tape may extend, a slide movably mounted on said flange within the casing, a cutter carried by said flange and extending outwardly through said opening to the exterior of the casing, and a radially extending tape-end-supporting lip on said flange, adjacent the opening, over which the cutter extends.
  8. A tape-dispensing device comprising a casing provided with a circular body portion having a circumferentially extending flange, means within the casing for rotatably supporting a roll of tape, said flange being provided with an opening through which the free end of the tape may

extend, a slide movably mounted on said flange within the casing, a cutter carried by said flange and extending outwardly through said opening to the exterior of the casing, said slide comprising a resilient member of arcuate shape disposed snugly against the inner surface of the flange, and a radially extending tape-end-supporting lip on said flange, adjacent the opening, over which the cutter extends.

9. A dispensing container for tape comprising a casing having a body portion and cover, said body portion being provided with a pair of openings spaced from each other, means temporarily sealing said openings against the entrance of air therethrough, and a slide within the casing, said slide comprising a resilient open ring-like member and having a projection adapted to extend through one of said openings and a projecting severing edge adapted to extend through the other opening, and a radially projecting lip on

said casing, adjacent said last-named opening, over which the severing edge extends.
